W. K. BAYLOR AND CONRAD RAPP, OF BATESVILLE, INDIANA

Letters Patent No. 88,769, dated April 13, 1869.

IMPROVEMENT IN KROUT-CUTTING MACHINE.

The Schedule referred to in these Letters Patent and making part of the same.

To all whom it may concern:

Be it known that we, W. K. BAYLOR and CONRAD RAPP, of Batesville, in the county of Ripley, and the State of Indiana, have invented a new and useful Improvement in Krout-Cutting Machines, of which the following is a full and clear description, reference being had to the accompanying drawings, making part of this specification.

Our invention relates to a double-edged cutter, secured to a reciprocating board; also, to the construction and arrangement of the mechanism for operating the machine, consisting of rack and pinions; and also, to a box and follower, located immediately over the cutter-board.

Figure 1 is a plan of our improved machine for cutting krouut.

Figure 2 is a longitudinal section of the same.

Figure 3 represents a longitudinal section of the frame, rack, and wheels.

Figure 4 represents a plan view, showing the construction of the wheels B D.

A is the frame-work of the machine.

The axle *a* is journalled in the frame A near one end. It is provided with the crank, or winch *b*, and also has secured to it, intermediate between its journal-bearing, the pinion B.

The cogs *c*, in length, equal to the thickness of the pinion.

The cogs *c'* are one-half the length of the cogs *c*, and are so located that the cogs *a* of the rack C do not engage them.

The pinion D, of the same size as the pinion B, and of the same construction, engages the pinion B.

The rack C is secured to the cutter-board E.

A double-edged knife, F, is secured to the board E, being located diagonally across it, to give a shearing-motion when operated.

The cutter-board E passes through openings in the bottom of the box G, which is secured to the frame A.

The box G is provided with the loosely-fitting follower H.

e is a lever, having one end pivoted to the standard *e'*, and its centre pivoted to the follower H.

Under the knife F is the perforation *f* in the cutter-board.

In operating the machine described in the foregoing, the power is applied to the winch *b*, or, in place thereof, a pulley or pinion may be connected with a motor.

The cogs of the pinion B constantly engage those of pinion D.

The short cogs *c'*, and also the long ones of each pinion, mesh into each other.

The pinions B and D rotate in opposite directions, hence, the motion given to the cutter-board E, by the alternate engaging of the rack C connected therewith, with the long cogs upon the pinions B and D, is reciprocal.

The krouut in the box G is pressed down beneath the follower H, by pressing upon the end of the lever *e*, and the knife or cutter F slices the krouut each time that it passes through the box, thus facilitating the operation by making two cuts in one operation.

We do not claim the mechanical movement herein described, nor do we claim a horizontally-reciprocating knife in a krouut-cutting machine.

What we do claim, is—

The arrangement of the wheels B D with cogs *c* and *c'*, rack C, board E, and knife F, with the frame A, and pressing-box G, in combination with each other, all substantially as set forth.

Witnesses:

O. L. FISHER,
W. J. NORTON.

W. K. BAYLOR.
CONRAD RAPP.
